Fig. 1

Fig. 2

Fig. 3

Fig. 4

Fig. 5

Fig. 6

FIG. 1 is a side elevational view of a toothpick or similar article, showing my design, the opposite side being a mirror image thereof;

FIG. 2 is a top plan view thereof;

FIG. 3 is a bottom plan view thereof;

FIG. 4 is a view of the left end thereof;

FIG. 5 is a view of the right end thereof;

FIG. 6 is a cross-sectional view taken along line VI—VI of FIG. 1.

The drawing is shaded to show a rough surface.

I claim:

The ornamental design for a toothpick or similar article, as shown and described.
